COMBINED ASH TRAY AND MARKER

Richard E. Loheide, 712 Highland Pike,
Covington, Ky. 41011

Filed July 24, 1972, Ser. No. 274,494

Term of patent 14 years

Int. Cl. D27—03

U.S. Cl. D85—2 P

FIG 4

FIG 6

FIG. 1 is a top plan view of a combined ash tray and marker showing my new design, the marker being removed for convenience of illustration;

FIG. 2 is an elevational view in the direction of arrows 2-2 in FIG. 1;

FIG. 3 is an exploded side elevational view of the ash tray and marker;

FIG. 4 is an elevational view of the assembled design;

FIG. 5 is a bottom plan view thereof; and

FIG. 6 is a sectional view taken on line 6-6 of FIG. 1.

I claim:

The ornamental design for a combined ash tray and marker, as shown and described.
